PULSATING DEVICE AND METHOD OF HONING

John E. Kline, Grosse Pointe Farms, Mich., assignor to Micromatic Hone Corporation, Detroit, Mich., a corporation of Michigan

Application August 29, 1941, Serial No. 408,711

3 Claims. (Cl. 51—34)

My invention relates to honing machines and methods and particularly to a device and method for modifying the reciprocating cycle of a honing tool during a honing operation.

It has been the practice in the art to reciprocate the honing tool within a cylinder to be machined with a stroke equal substantially to the full length of the cylinder, and superimpose upon said stroke a vibratory movement for the purpose of materially breaking up the scratch marks on the cylinder wall. The superimposed vibration, or reciprocation, on the stroking reciprocating movement produces faster cutting as well as a finer finish on the cylinder surface. Mechanical means were employed for superimposing the oscillation or short stroke reciprocation to the honing tool, and I find that I can not only accomplish the same result by manipulating the flow of the fluid during the reciprocating cycle, but can actually reverse the movement of the tool relative to the surface as the tool is advanced thereacross.

I connect a cylinder in the pressure circuit and drive the piston thereof in reciprocation for alternately affecting the volume of fluid delivered to the cylinder that reciprocates the honing tools. In this manner, the natural cycle of reciprocation is retarded and accelerated a number of times during each normal stroking movement. On the suction stroke of the piston, the delivered volume is reduced so that the stroking cylinder for the tool is retarded and preferably reversed. On the compression stroke of this piston, the delivered volume is increased, which accelerates the stroking cylinder for the hone, above its normal speed of movement. This action simulates the action of superimposing a reciprocating movement on the stroking movement of the tool and differs therefrom in actually reversing the movement of the tool relative to the surface being honed as the tool is advanced across the surface.

Accordingly, the main objects of my invention are to accelerate and decelerate the movement in reciprocation of a honing tool by fluctuating the volume of fluid which reciprocates the tool; to accelerate and decelerate the movement of a honing tool by cyclically varying the volume of the fluid system; to accelerate and decelerate the speed of movement of a reciprocating piston by pulsating the fluid in the system which reciprocates the piston; to connect a cylinder in a fluid pressure system and operate a piston therein in reciprocation to vary the delivery volume in the system and accelerate and reverse the

movement of a honing tool during its normal cycle of reciprocation; and, in general, to provide a method for cyclically changing the movement of a honing tool in reciprocation which is simple in construction and positive in operation.

Other objects and features of my invention will be specifically pointed out or will become apparent when referring, for a better understanding of my invention, to the following description, taken in conjunction with the accompanying drawing, wherein:

Fig. 1 is a diagrammatical view of a system for operating a honing tool in rotation and reciprocation while practicing my invention;

Fig. 2 is a view of the pulsating cylinder shown in Fig. 1, illustrating a modified form of operating mechanism therefor.

I have illustrated one or a plurality of honing tools 10 of conventional form having a plurality of abrasive stones 11, which are expandable by suitable means, such as a spring, a fluid or the like. In the tool illustrated, a spring is utilized as the expanding means, while cam fingers 12, operated by a cam plate 13, render the spring effective to expand the stones. The honing tool is supported on a shaft 14, which is driven in rotation by a plurality of gears 15 operated from a spline shaft 16. The head 17 is mounted for reciprocation on slide bars 18 when suspended from a piston rod 19, on which a piston 21 is mounted, within a cylinder 22. Conduits 23 and 24 are connected to opposite ends of the cylinder 22 and to opposite ends of a cylinder 37. A tank 26 contains a fluid 27, such as oil, which is circulated by a pump 28, through a conduit 32 to a four-way valve 25. The fluid is returned to the tank from the four-way valve 25 through a metering or speed regulating valve 30 and conduits 33 and 34. The pressure on the liquid delivered from the conduit 32 is controlled by the regulating valve 31 connected to a conduit 29 and to the return conduit 34.

A conduit 36 from the valve 25 is connected to the conduit 24 which is joined to the right hand end of the cylinder 37, as viewed in Fig. 1. A piston 38 operates in the cylinder 37 on a piston rod 39, which is reciprocated by a cam plate 41. The piston rod is the same diameter on both sides of the piston to move equal volume of liquid each time the piston is reciprocated. The crank is driven from a shaft 42 on which a flywheel 43 is mounted. A conduit 40 connects the opposite side of the valve 25 to the front end of the cylinder 37, as viewed in the figure.

In operation, when the piston 21 is moving

downwardly from the position illustrated, the valve 25 has been moved to connect the fluid in the pressure line 32 through the conduit 41 to the fluid end of the cylinder 37. The rear end of the cylinder 37 is connected through the conduit 36 to the valve 25 and through the conduits 33 and 34 to the tank. The flow of liquid to the tank, however, is controlled by the metering and speed regulating valve 30 which produces a back pressure on the lower end of the cylinder 22 and the rear end of the cylinder 37. As liquid is delivered through the conduit 32, the valve 25, conduit 40, through the cylinder 37, conduit 23, into the upper end of the cylinder 22, the piston 21 is moved downwardly, forcing the liquid through the conduit 24 into the rear end of the cylinder 37 and through the conduit 36, the valve 25, valve 30, conduits 33 and 34, to the tank.

During the flow of fluid in this manner, the piston 38 in the cylinder 37 is rapidly reciprocated, providing a pulsation to the fluid on both sides of the piston 21, which may retard, arrest, or reverse, while accelerating, the downward movement of the piston, depending upon the relative size of the cylinders 37 and 22.

When the piston approaches the end of its downward movement, the finger 57 strikes the collar 56 on the rod 54 to reverse the pilot valve 48, which operates the valve 25, to reverse the flow of fluid in the conduits 36 and 40. The piston 21 is then moved upwardly and will be retarded, arrested, or reversed, while being accelerated in the same manner, as pointed out hereinabove relative to the down stroke of the piston. The number of reciprocations superimposed on the piston 21 per cycle of its reciprocation is regulated by the number of strokes of reciprocation of the piston 38.

The acceleration and the retarding, arresting or reversal of the movement of the tool in its normal cycle of reciprocation, breaks up any harmonic pattern of scratch marks on the cylinder wall and more rapidly abrades the cylinder wall. The actual reversal of the movement of the tool during its normal cycle of reciprocation breaks down the abrasive stone face thereof and eliminates glazed surfaces, to thereby increase the cutting effect of the abrasive particles which produces faster abrasion and a fine degree of finish to the cylinder wall.

A pilot control circuit 47 is connected between the pressure line 29 and a pilot valve 48. The pilot valve is connected by conduits 49 and 51 to one or the other of the four-way valve 25 and is operated by a rack 52 and pinion 53, mounted on a rod 54. Collars 55 and 56 are adjustable on the rod 54 to regulate the length of stroke of the piston 21. The rod is moved at the end of each stroke by a finger 57 which projects between

the collars. A dwell valve 58 is connected in the system by conduits 59 and 61, which controls the time for additional stroking of the piston 21 and tool 10 after the abrading operation has been completed and a handle 62 of the valve has been operated to "off" position.

In Fig. 2, I have illustrated a modified form of drive mechanism for the piston rod 39, wherein a roller 44 is attached to the end of the rod in contact with a cam 45 on the shaft 42, on which a fly wheel 43 is mounted. The pressure in the system forces the piston 38 to the right, as viewed in the figure, thereby maintaining contact between the roller 44 and the cam 45, in all positions of the cam. In view of the resistance to the movement of the piston 38 on its forward stroke, the fly wheel 43 expends energy to reduce the amount of power required to operate the shaft 45 and any shock to the operating mechanism.

While I have described and illustrated but two embodiments of my invention, it will be apparent to those skilled in the art that various changes, omissions, additions and substitutions may be made therein without departure from the spirit and scope of my invention, as set forth in the accompanying claims.

What is claimed is:

1. In a system for honing a cylinder, the combination including a honing tool, a piston and cylinder which produces the reciprocation of the honing tool within a working stroke, a system for delivering fluid to opposite sides of the cylinder, means for reversing said flow of fluid to said cylinder, and means for pulsating the flow of the fluid.

2. The combination in a honing machine, a honing tool, a cylinder having a reciprocable piston, a fluid pressure system connected to each end of said cylinder, valve means for reversing the flow of the fluid to said cylinder, a pump for delivering fluid to said system and a cylinder connected in the pressure system having a piston therein which alternately decreases and increases the volume of fluid supplied to the first said cylinder when said last piston is reciprocated.

3. The combination in a honing machine, a honing tool, a cylinder and piston in said machine for operating said honing tool in reciprocation, a valve, a fluid pressure system connected directly to said valve and from said valve to the opposite ends of the cylinder, means for operating said valve for reciprocating said piston, a second cylinder connected in said fluid system, a piston reciprocated in said cylinder at a higher rate of speed than said first piston for changing the volume of flow on said first piston above and below the normal volume during a single cycle of its reciprocation.
